UNITED STATES PATENT OFFICE.

JOSEPH M. JONES, OF PARIS, KENTUCKY.

DESIGN FOR A CAMPAIGN BUTTON.

SPECIFICATION forming part of Design No. 18,571, dated August 28, 1888.

Application filed July 27, 1888. Serial No. 281,140. Term of patent 3½ years

To all whom it may concern:

Be it known that I, JOSEPH M. JONES, of Paris, in the county of Bourbon and State of Kentucky, have invented and produced a new and original Design for a Campaign Button, of which the following is a full, clear, and exact specification.

Reference is had to the accompanying drawing, which forms part of this specification, and which represents a face view, upon an enlarged scale, of a campaign button having my new design.

The button is ornamented on its face with a background, A, representing a portion of a bandana handkerchief of circular marginal contour, and with a figure, B, in its center representing the Stars and Stripes or national flag of the United States of America.

I claim—

The design for a campaign button herein shown and described, the same comprising a background on the face of the button representing a portion of a bandana handkerchief of circular marginal contour, and a figure in its center representing the Stars and Stripes or national flag of the United States of America, as set forth.

JOSEPH M. JONES.
